UNITED STATES PATENT OFFICE.

SAMUEL BUYER, OF YONKERS, NEW YORK.

DESIGN FOR A MERCHANTISE-DISPLAY STAND.

42,684.

Specification for Design.

Patented July 2, 1912.

Application filed March 19, 1912. Serial No. 684,822. Term of patent 3½ years.

To all whom it may concern:

Be it known that I, SAMUEL BUYER, a citizen of the United States of America, residing at Yonkers, Westchester county, in the State of New York, have invented a new, original, and ornamental Design for Merchandise-Display Stands, of which the following is a specification, reference being had to the accompanying drawing, forming part hereof, which represents a perspective view of a merchandise-display stand, showing my new design.

I claim:

The ornamental design for a merchandise display stand, as shown.

Signed at New York city, New York, this 16th day of March, nineteen hundred and twelve.

SAMUEL BUYER.
